UNITED STATES PATENT OFFICE.

OTTO J. KUHLKE, OF AKRON, OHIO, ASSIGNOR TO THE KUHLKE MACHINE COMPANY,
OF AKRON, OHIO, A CORPORATION OF OHIO.

COLLAPSIBLE CORE.

Application filed September 2, 1924. Serial No. 735,265.

This invention relates to collapsible cores or forms for the building of pneumatic automobile tires of the type characterized by the fact, that the sections are provided with a collapsing mechanism to withdraw them to the interior of the tire bead, all of the mechanism being permanently secured to the shaft.

The object of the present invention is to improve upon collapsible cores of this type by increasing the ease and rapidity of operation of the core, and by so constructing the core that in collapsed position, it will occupy less space than other cores of a similar type, and to facilitate the removal of the tire. The core is, therefore, suitable and adaptable for the manufacture of the so called "balloon type" tires which are characterized by a large cross section and small bead diameter.

It is the purpose of the invention to construct a core in which a plurality of sections are hinged together by oblique or diagonal hinges, similar in this respect to the construction shown in my prior Patent No. 1,490,468 dated April 15, 1924, but differing from that patent in the respect that the sections move to the same side of the central or fixed section, whereas in the former patent, the core sections moved in opposite directions. By this construction I am enabled to utilize the oblique hinge construction without interfering with certain supporting and collapsing mechanism at the rear of the core.

A further object of the invention is to construct a form of collapsing mechanism in which a group of the core sections is movable in a curved path to a position outside of or intersecting the original core plane, leaving a key section in fixed position, so that after such movement has taken place, the section of the group may be collapsed without interfering with the key section.

The broader aspects of the present invention are covered in my application, Serial No. 747,913, filed November 5, 1924, which is a continuation in part of the common subject matter.

These and other objects will be apparent from the description and drawings of the invention forming a part of the specification, it being understood that the invention may be embodied in other forms and other mechanisms than shown and described. Such

modifications and alterations as fall within the scope of the invention as set forth in the appended claims, are intended to be covered herein.

In the drawings which illustrate one form of the invention,

Fig. 1 is a front elevation of the core in complete or circular condition.

Fig. 2 is a horizontal section on the line 2—2 of Fig. 1.

Fig. 3 is a vertical section on the line 3—3 of Fig. 1.

Fig. 4 is a view similar to Fig. 3 but showing the first movement in the collapsing operation.

Fig. 5 is a detail section on the line 5—5 of Fig. 1.

The core may be divided into any number of sections as may be found desirable. In the drawing, it is divided into a key section 1, which is mounted independently of the other section and three sections 2, 3 and 4, which constitute the balance of the core and which are hinged together, the section 4 being a central or fixed section and the sections 2 and 3 being hinged sections, the key section fitting between the ends of the hinged sections to complete the core when in circular condition.

The shaft for supporting the core is indicated by the numeral 5 and to the outer end of the shaft is keyed the main supporting plate 6. At the outer end of the supporting plate is mounted a hinge pin 7, which passes through ears 8 formed on the interior of an arc shaped plate 9 which is attached to the inner periphery of the key section 1. Lugs 10 are formed on the supporting plate 6 and on the ears 8 are provided stops 11 which contact the lugs 10 and halt the swinging movement of the key section so that it is located in vertical position as indicated in Fig. 3. The key section is, however, free to swing outwardly in the collapsing of the core until it is freed from the tire, whereupon it will swing back to its vertical position.

The remaining core sections 2, 3 and 4 are hinged together and move as a group or unit. For this purpose, there is attached to the central or fixed section 4 an arc shaped bracket 12 from which extend, in the direction of the core axis, two parallel arms 13 and 14, the lateral faces of which are somewhat fan-shaped, and are formed with

facing, parallel grooves or slideways 15 which slide upon curved parallel rails or guides 16 formed as a part of the supporting plate 6. It will be seen that if the core sections 2, 3 and 4 are allowed to move as a group or unit upon the guideways 16, the section 4 will approach the core shaft 5 and the whole group will assume a position in a plane intersecting with the original 10 core plane, and that the key section 1 will swing outwardly until it is free of the tire and then reassume its vertical position.

One of the brackets, shown as 14, is provided with an arc shaped rack 17 above the 15 groove 15, and with the rack is meshed a pinion 18 rotatably mounted in the front of the supporting plate, formed with a squared extension 19 for operation by a wrench. The pinion may be utilized for 20 raising or lowering the group of core sections, although by turning the core in proper position, the force of gravity will perform this operation. A spring held pawl or dog 20 may engage the pinion for 25 preventing accidental collapsing of the core.

The sections 2 and 3 are hinged to the central or fixed section 4 so that they can be moved inwardly after the core has been collapsed into the position shown in Fig. 30 4. For this purpose any type of hinge may be used, but in the present invention, I prefer to make use of the oblique or angled hinge. The hinges between the sections are indicated at 21 and 22, and, as shown in Fig. 35 2 are obliquely arranged with respect to the core plane so that at the same time that they are swinging inwardly or toward the center of the core, they are swinging outwardly to clear the core section. In the present invention the hinge 22 is arranged at a greater 40 angle to the core plane than the hinge 21 so that the section 2 swings outwardly to a greater extent than the section 3. By this construction the section 3 will pass beyond 45 the section 4, and the section 2 will clear both of said sections.

It will be seen that I have provided a simple and easily operated collapsible core which will collapse into an exceedingly 50 small diameter to permit the removal of the tire. The claims appended hereto are intended to cover the invention as broadly as permitted by the state of the prior art and cover such modifications and alterations as 55 would be suggested to those skilled in the art.

It will be understood that the invention may be applied to all tire building forms,

whether of the rounded core shape or not and the claims are not necessarily limited to 60 the exact shape of the core. Where the term "core" is used throughout the specification and claims it will be understood that "form" is the equivalent thereof.

What is claimed is:

1. A collapsible core comprising a central supporting plate, a plurality of sections constituting the core, one of the sections being hinged to the said plate, the remaining sections being hingedly connected together in 70 a group, a guiding formation on the central plate, curving outwardly from the core plane and means carried by the group of sections to engage said formation, whereby the group of core sections may be moved to 75 a position intersecting the original core plane.

2. A collapsible form comprising a form section, a curved arm attached to the form section and projecting toward the axis of 80 the form, means to support the arm for sliding movement and intermediate form sections carried by the first named form section.

3. A collapsible core comprising a core 85 section, a curved arm attached to the core section and projecting toward the axis of the core, means to support the arm for sliding movement and a second core section carried by the first named core section.

4. A collapsible core construction embodying a supporting plate, a guiding formation upon the plate, a curved arm having sliding engagement with the plate, a core section carried upon the arm, a second core 95 section carried upon the plate and hinged core sections lying between the ends of the aforementioned sections.

5. A collapsible core construction embodying a supporting plate, a guiding formation upon the plate, a curved arm having sliding engagement with the plate, a core section carried upon the arm, a second core section carried upon the plate, and pivotally mounted core sections lying between the 105 ends of the aforementioned sections, the hinges of the pivots being angularly arranged with respect to the core plane.

6. In a collapsible core construction, a rigid section and a swinging section hinged to each end of the rigid section, the axes of the hinges being inclined in the same direction relative to the plane of the core but to different predetermined angular extents.

OTTO J. KUHLKE.
